UNITED STATES PATENT OFFICE.

GEORGE W. KING, OF INDIAN SPRINGS, TENNESSEE, ASSIGNOR OF ONE-THIRD TO
J. NAT BOWERY, OF INDIAN SPRINGS, TENNESSEE.

CHURN.

1,089,772.

Specification of Letters Patent. Patented Mar. 10, 1914.

Application filed July 12, 1913. Serial No. 773,805.

To all whom it may concern:

Be it known that I, GEORGE W. KING, a citizen of the United States, residing at Indian Springs, in the county of Sullivan and State of Tennessee, have invented a new and useful Churn, of which the following is a specification.

The device forming the subject matter of this application is a churn, of that general type in which superposed dashers are rotated in opposite directions by a common driving train.

One object of the invention is to provide novel means whereby the space between the dashers may be adjusted.

Another object of the invention is to provide novel means for holding one dasher in place upon its actuating shaft.

It is within the scope of the invention to improve generally and to enhance the utility of, devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawing:—Figure 1 shows the invention in side elevation, the churn receptacle being sectioned; Fig. 2 is a side elevation, the structure being viewed at right angles to the showing of Fig. 1, parts being broken away and sectioned; Fig. 3 is a top plan of a head which receives one dasher; and Fig. 4 is a plan view applicable to both dashers.

In carrying out the invention there is provided a receptacle 1 which may be of any desired shape, size and capacity. A supporting structure for the driving mechanism of the churn is provided and this supporting structure includes a closure for the upper end of the receptacle 1, the closure comprising a fixed section 2 and a movable section 3, the sections 2 and 3 being united by hinges 4. The sections 2 and 3 of the closure are shouldered as shown at 5 so as to fit down into the top of the receptacle 1.

Secured to the fixed section 2 of the closure is a primary frame denoted generally by the numeral 6, the frame 6 comprising a top bar

7, side bars 8 and a bottom bar 9, the latter being secured directly to the fixed section 2 of the closure. The side bars 8 of the primary frame 6 terminate in thinned fingers 10 adapted to overlap the outer face of the receptacle 1 and to cooperate with the shoulder 5 of the closure in holding the support for the driving mechanism in place on the upper end of the receptacle 1.

The invention further includes a secondary frame denoted generally by the numeral 11, the frame 11 standing at right angles to the primary frame 6. The secondary frame 11 includes vertical standards 12 and 14, the lower ends of which are secured to the fixed section 2 of the closure. The standard 12 includes a thinned finger 13 coöperating with the fingers 10 to accomplish the end above stated. The secondary frame 11 further includes a top bar 16 connecting the upper ends of the standards 12 and 14, the top bar 16 overlapping the top bar 7 on the primary frame 6.

The invention includes a vertical shaft 17 which is journaled for rotation in the top bars 7 and 16, in the bottom bar 9 and in the fixed section 2 of the closure, the lower end of the shaft 17, which may be denominated the dasher shaft, projecting downwardly into the receptacle 1. To the upper end of the dasher shaft 17 may be applied a nut and washer 18 or any other suitable means for retaining the dasher shaft 17 against downward movement in the primary frame 6. Secured to the dasher shaft 17 below the top bar 7 of the primary frame 6 is a pinion 20 which may include a neck 21 provided with a set screw 22 engaging the dasher shaft 17.

Disposed at right angles to the dasher shaft 17 and journaled in the standards 14 and 12 is a drive shaft 23 provided at its outer end with a crank 24 or any other suitable means whereby the drive shaft may be actuated either by hand or from a prime mover. Fixed to the inner end of the drive shaft 23 is a relatively large gear wheel 25 which meshes into the pinion 20. At its lower end, the dasher shaft 17 is provided with a socket 31 into which a set screw 32 is threaded. Journaled on the dasher shaft 17 above the socket 31 and extended upwardly through the fixed section 2 of the closure and through the bottom bar 9 of the primary frame 6 is a sleeve 26 to the upper

end of which is secured a pinion 19 meshing into the gear wheel 25 at a point diametrically opposite to the pinion 20. The pinion 19 co-operates with the bottom bar 9 to prevent the sleeve 26 from moving downwardly. Secured to the lower end of the sleeve 26 and disposed transversely thereof is a head 27 which is located directly above the socket 31 on the lower end of the dasher shaft 17. Adjacent its ends, the head 27 is equipped with vertical openings 28, there being set screws 29 threaded into the ends of the head 27 and adapted to co-operate with the openings 28. The openings 28 in the head 27 are alined with vertical grooves 30 formed in the outer face of the sleeve 26.

The agitating mechanism includes a lower dasher 33 which is secured to the lower end of a shaft 34, the upper end of the shaft 34 being inserted into the socket 31 of the dasher shaft 17 and being held therein by the set screw 32. An upper dasher 35 is provided and projecting upwardly from the dasher 33 are converging, resilient arms 36. The arms 36 pass through the openings 28 in the head 27 and are adapted, at their upper ends to ride in the grooves 30 of the sleeve 26. The dashers 33 and 35 may be of any desired form. As shown in Fig. 4, they may comprise angularly disposed intersecting bars 37, concaved at their ends as indicated at 38. This specific form of dasher shown, however, is not mandatory.

In practical operation, the drive shaft 23 is rotated through the medium of the crank 24 or its equivalent, and rotatory movement is thereby imparted to the large gear wheel 25, the same meshing into the pinion 20 and rotating the shaft 17, the shaft 17 rotating the shaft 34, and the latter imparting rotation to the lower dasher 33. When the large gear wheel 25 is rotated, motion will be transmitted through the pinion 19 through the sleeve 26 and to the head 27 which is secured to the lower end of the sleeve. Motion will thus be transmitted to the arms 36 and thence into the upper dasher 35. From

the foregoing it will be observed that when the shaft 23 is rotated, the dashers 35 and 33 will rotate in opposite directions, securing a thorough agitation of the contents of the receptacle 1. By loosening the set screws 29, the arms 36 may be slid up and down in the openings 28 of the head 27, the upper ends of the arms riding in the grooves 30 of the sleeve 26. In this manner, the space between the dashers 35 and 33 may be adjusted.

Owing to the provision of the head 27, having openings 28, and the sleeve 26 having grooves 30, the arms 36 are firmly assembled with the sleeve 26 for rotation in one piece, the vertical adjustment of the arms 36 and the dasher 35, however, being effected readily, in the manner hereinbefore set forth.

Having thus described the invention, what is claimed is:—

1. In a churn, a receptacle; a shaft; means for supporting the shaft for rotation; a transverse head secured to the shaft and having openings located upon opposite sides of the shaft; a dasher located in the receptacle and provided with converging arms engaged in the openings and bearing against the shaft above the head; and arm-engaging clamping means carried by the head and co-operating with the openings.

2. In a churn, a receptacle; a shaft having opposed longitudinal grooves; means for supporting the shaft for rotation; a transverse head secured to the shaft and having openings alined with the grooves; a dasher located in the receptacle; and resilient arms secured to the dasher, the arms passing through the openings in the head and registering in the grooves.

In testimony that I claim the foregoing as my own, I have hereto affixed my signature in the presence of two witnesses.

GEORGE W. KING.
